DESIGN FOR A COMBINED RANGE TIMER AND CONDIMENTS HOLDER

Elmer D. Pellegrin, Woodstock, Ill., assignor to
Geo. D. Roper Corporation, Rockford, Ill., a cor-
poration of Illinois

Application April 14, 1941, Serial No. 100,371

Term of patent 7 years

To all whom it may concern:

Be it known that I, Elmer D. Pellegrin, a citizen of the United States, residing at Woodstock, in the county of McHenry and State of Illinois, have invented a new, original, and ornamental design for a Combined Range Timer and Condiment Holder, of which the following is a specification, reference being had to the accompanying drawing, forming part thereof.

In the drawing:

Fig. 1 is a front elevational view of a combined range timer and condiment holder showing my new design;

Fig. 2 is a top plan view thereof; and
Fig. 3 is an end elevational view thereof.

In these views the stippled surfaces indicate contrasting colored areas.

The dominant features of the design are those shown in full lines.

I claim:

The ornamental design for a combined range timer and condiment holder, substantially as shown and described.

ELMER D. PELLEGRIN.
